UNITED STATES PATENT OFFICE

2,170,161

COLLAPSIBLE COPY HOLDER

Stephen Sattler, Tulsa, Okla.

Application October 2, 1937, Serial No. 166,961

7 Claims. (Cl. 120—32)

The present invention relates to copy holders, and more particularly to copy holders for use with typewriters of standard makes, both with narrow and wide carriages, which holders may be collapsed so as to fit within typewriter desks of present design.

The present invention is an improvement over applicant's Patent No. 1,715,472, issued June 4, 1929.

An object of the present invention is to provide a copy holder capable of use with any standard make of typewriter and one which is capable of receiving paper of various widths, even paper of greater width than that of the copy holder.

Another object of the present invention is to provide a copy holder, for use with typewriters, having a revolvable paper feeder capable of accommodating varying widths of paper from narrow strips such as one inch, to paper thirty-five 20 inches or more in width.

A further object of the present invention is to provide a copy holder including a revolvable platen and holding means in cooperation therewith, which means are urged against the platen by spring action, to form a grip for copy between the holding means and the platen, irrespective of the thickness of the copy, to assure sufficient frictional engagement between the holding means and platen for step-by-step movement of the 30 copy as desired.

The invention has for an additional object the provision of a copy holder arranged for supporting copy vertically behind a typewriter, whereby the copy may be readily observed by the typist, and which holder is collapsible into a space sufficient to be included within the ordinary desk.

The invention has for an additional object the provision of a collapsible copy holder, for use with typewriters, with means for holding copy in vertical position in front of a typist, which means include a revolvable platen and holding means, the platen and holding means being collapsible and extensible simultaneously.

A still further object of the present invention is to provide means for holding copy against a revolvable platen, which means are spring-pressed and capable of adjustment for varying the spring pressure.

The above, other, and further objects of the present invention will be apparent from the following description and accompanying drawings.

An embodiment of the present invention is illustrated in the accompanying drawings, and the views thereof are as follows:

Figure 1 is a fragmental isometric view of a

copy holder, showing the same in extended position, and showing the relationship of some of the parts when in extended position.

Figure 2 is an end elevational view of the arrangement of Figure 1, showing in full lines the parts as extended, and in dotted lines the parts in collapsed position.

Figure 3 is a fragmental sectional view taken in the plane of line III—III of Figure 1.

Figure 4 is a view in front elevation, showing the holder extended, and in full lines the arrangement of the parts when the copy is of width no greater than that of ordinary typewriter paper, and in dotted lines the adjustment of certain of the parts to accommodate copy of greater width.

Figure 5 is an enlarged, fragmental, end view, looking at the right hand end of Figure 4, with the end cover plate removed, and showing mechanism for advancing the platen.

Figure 6 is a fragmental vertical sectional view taken substantially in the plane of line VI—VI of Figure 4, showing in full lines the relationship of parts when in normal position, and in dotted lines the relationship of certain of the parts brought into play to collapse the holder.

Figure 7 is a fragmental horizontal sectional view taken substantially in the plane indicated by line VII—VII of Figure 4.

Figure 8 is an enlarged fragmental vertical sectional view taken substantially in the plane indicated by line VIII—VIII of Figure 7, showing in full lines the parts in normal position, and in dotted lines the position assumed when the line guide is moved away from the platen, and illustrating the manner in which tension is applied to the line guide.

Figure 9 is an end elevation of the copy holder of the present invention in extended or operative position looking at the right-hand side of the same.

The drawings will now be explained.

The illustrated embodiment of the present invention consists of two portions, a lower frame portion A and an upper frame portion B.

The lower frame portion A includes a base member 1, on which are suitably supported two upright rods 2 and 3, connected at their upper ends by a cross bar 4. The lower ends of the rods 2 and 3 are mounted in collars 5 and 6 suitably secured to the base 1.

The upper frame member consists of two side members 7 and 8, fashioned from flat metal. The lower ends of the side members 7 and 8 are inturned forming feet 9' and 10', which feet are 55

apertured to receive the rods 2 and 3 as guides for vertical movement of the upper frame member B.

The upper portions of the side members 7 and 8 carry a platen 9 on a shaft 10 which is suitably supported. Disposed on the outer surface of the side member 8, is a mechanism for imparting step by step movement to the platen. The mechanism for operating the platen is that of applicant's aforesaid Patent No. 1,715,472.

At each end of the shaft 10 are the usual knobs 11 and 12 for rotating the platen by hand.

Connected to the side members 7 and 8 in a position to abut the cross bar 4 of the lower frame member A, and thus limit upward movement of the upper frame member B, is an angle bar 13 welded or otherwise secured to the side members 7 and 8. As may be observed in Figures 1 and 4, this bar 13 contacts the under side of bar 4 when the copy holder is extended.

The mechanism for locking the upper frame member B in extended position comprises two levers 14 and 15 which extend along the inner surfaces of the side members 7 and 8, above the bar 13, and which are pivoted at 16 and 17 respectively to the side members 7 and 8 below the mid-points of the levers. Connecting the lower ends of the levers 14 and 15 is a rod 18 so arranged that when the upper frame member is extended, the rod will rest against the upper side of bar 4 and thus lock the upper frame member B in extended position. The ends of the rod 18 may be enlarged at 19, to serve as abutments for engaging the bar 4, in which event the rod 18 would be out of contact with the bar 4. For normally maintaining the rod 18 in locked or latched engagement with the bar 4, springs 20 are arranged to act against the levers 14 and 15, above their pivots, to normally urge the lower ends of the levers to the left, as viewed in Figure 1, that is into locking or latching position with respect to the bar 4.

For unlatching the upper frame member for collapse, a rod 21 is pivoted in the side members 7 and 8 and arranged along the rear margin of the bar 13. At the left hand end of the device, as viewed in Figures 1 and 4, as well as in Figure 2, it will be observed that the rod 21 extends through the side wall member 7 where at its outer end it is fastened to a crank 22 which normally is in substantial horizontal position, as viewed in Figure 2.

Pivoted at 22' to the outer face of the side member 7 is a bell crank C, with one leg 23 extending upwardly from the pivot and provided at its extremity with a surface 24 constituting a thumb latch.

The other arm 25 of the bell crank extends downwardly in an inclined direction from the pivot 22', where at its lower end it carries a pin 26 entered in a slot 27 in a vertically disposed, slotted operating bar 28. The pin 26 has a head inwardly of the bar 28 in position to engage the crank 22 when the thumb latch 24 is moved in counterclockwise direction as viewed in Figure 2.

Secured to the rod 21, inwardly of the side members 7 and 8, are curved crank arms 29 having their free ends in register with the front edge margins of the levers 14 and 15, as may be observed in Figures 1 and 2.

To release the upper frame member B for collapse, the thumb latch 24 is moved in counterclockwise direction, as viewed in Figure 2, whereupon the pin 26 will engage the crank 22 and move it in counterclockwise direction, thus

swinging the curved cranks 29 against the levers 14 and 15 moving the lower ends thereof backwardly of the bar 4, so that the ends of the levers and the rod 18 are freed from engagement against the bar 4, whereupon the upper frame member may be lowered to the dotted line position of Figure 2.

Cooperating with the platen 9, to support copy against it for line by line advancement, is a line guide member designated generally at D, including a cross head 30 of substantially the same length as the platen 9, and two depending hollow legs 31 and 32 arranged near the respective ends of the cross head.

For cooperating with the legs 31 and 32, vertically disposed rods E and F having L-shaped feet are supported on the base 1.

The rod E has a lateral horizontal foot portion 33 and a vertical portion 34, while the rod F has a lateral foot portion 35 and a vertical portion 36. The lateral foot portions 33 and 35 abut endwise within a clip 37 secured by screws 38 to the base along its front margin, for rocking movement. Extending rearwardly from the angle between the portions 33 and 34 of the rod E, is an integral foot extension 37 having a flattened end 38. In like manner, extending rearwardly from the angle of the rod F, is a similar foot extension 39 having a flattened end 40.

Supported for rocking movement along the rear margin of the base 1 is a shaft 41 having flattened portions 42 and 43, which normally receive the flattened ends 38 and 40 of the extensions 37 and 39, of the rods E and F when the device is in operative position. The shaft 41 is supported in clips 44 and 45 fastened by screws 46 to the base, as may be observed in Figure 7. Fastened to the left hand end of the shaft 41, as viewed in Figure 7, is a crank 47 which at its outer end is pivotally connected as 48 to the slotted bar 28.

At the other end of the base 1, that is the right hand end as viewed in Figure 7, the shaft 41 carries a mutilated gear 49 in mesh with the teeth 50a of an arm 50 pivoted by means of a screw 51 to this end of the base. The arm 50 has an upstanding part provided with an outstanding end 52 for overlying the lever 53 pivoted at 54 to the base. The lever 53, outwardly of its fixed pivot 54, is pivoted to another 50 pivoted lever which in turn carries at its free end a key 55 adapted to be contacted by a finger of the typist to operate the platen in step by step movement.

Pivoted to the end of the lever 53, adjacent the arm 50, is an upright member 56 which at its upper end carries a pin 56' entered in a slot 57 in an actuating bar 58 which works the platen.

The depending legs 31 and 32, of the line guide structure D, at their lower ends encircle and receive the upright portions 34 and 36 of the rods E and F and are slidable along these portions in telescopic arrangement. The lower ends of the legs 31 and 32 are provided with elongated cylindrical portions 59 and 60 for surrounding the uprights of the rods E and F.

Pivoted at 61, to the legs 31 and 32 of the line guide D, are locking bars 62 extending along the legs. The lower ends of the bars 62 are shown as L-shaped, as at 63', and normally engage 70 against the upper extremities of the vertical portions 34 and 36 of the rods E and F to latch the line guide device in extended position, as may be observed in Figure 2.

The cross head 30 is provided with a roller 63 75

which is maintained, normally, against the platen 9 by means of the springs hereinafter described.

The flattened ends 38 and 40 of the extensions 37 and 39 of the rods E and F, are apertured as at 64 (Figure 8) with screws 65 passed through the aperture 64 in the flattened ends of the extensions 37 and 39 and threaded into the base 1. The screws are headed at 66. Surrounding the screws, between the extensions 37 and 39, of the rods, and the heads 66 of the screws, are springs 67 tensioned to hold the extensions 37 and 39 against the base and the roller 63 against the platen. By adjusting the screws 65 the action of the springs 67 may be varied to correspondingly vary the pressure of the roller 63 against the platen.

The effort exerted by the springs 67 tends to maintain the roller 63 in contact with the platen 9 to urge copy against the platen for advancement as the platen is given step by step rotative movement, as hereinafter described.

Guided in the upper ends of the side members 7 and 8, for horizontal movement, are plungers 10 operatively connected to the upper ends of the levers 14 and 15, by pins 11 carried by the plungers entered in notches 12 formed in the levers. The cross head 30 is apertured to allow the reduced ends 13 of the plungers passage through the cross head.

The upper ends of the locking bars 62 have integral plates 74 in the paths of movement of the plungers 10.

Normally the plungers 10 are retracted, as shown in Figure 6. As the plungers are moved outwardly, that is, to the left as viewed in Figure 6, by swinging of the levers 14 and 15, the reduced ends 13 of the plungers pass through apertures in the crosshead 30 and engage the plates 74 at the upper ends of the bars 62, thus bringing the upper ends to the right, as viewed in Figure 2, and the lower ends to the left, which moves the lower ends out of register with the upper ends of the rods E and F, thus unlatching the line guide structure D, ready for collapse.

Movement of the plungers 10 to the left, as viewed in Figure 6, and to the right as viewed in Figure 2, causes entry of the reduced ends 13 of the plungers into the apertures in the line guide structure D, thus connecting the line guide structure to the upper frame member B of the device. As the levers 14 and 15 are rocked, as heretofore described, the bar 18 connected to the lower ends of the levers 14 and 15, drops behind the rods 2 and 3 and remains behind the rods 55 until the upper frame member B is again extended to operative position. By reason of the fact that the levers 14 and 15 remain tilted out of engagement, by reason of the position of the rod behind the rods 2 and 3, the plungers 10 are maintained in outward or projected position in connection with the line guide structure D to connect the line guide structure to the upper frame member for simultaneous movement with it, downwardly or upwardly, that is to say, into inoperative or operative position.

When the upper frame member is raised or extended, which is done by the operator grasping the knobs 11 and 12 and raising the upper frame structure, and as soon as the upper frame member reaches its uppermost position, the springs 20 become effective to move the lower ends of the levers 14 and 15 over the bar 4 thus latching the upper frame member in extended position. Movement of the levers in this manner retracts the plungers 10, whereupon the locking bars 62,

carried by the legs 31 and 32 of the line guide device C, by virtue of the action of spring 125 swing into normal vertical position with their lower ends against the upper ends of the vertical portions 34 and 36 of the rods E and F, thus latching the line guide device in extended position.

It will be observed that the upper frame member and the line guide device are raised and lowered simultaneously. The engagement of the plungers 10 with the line guide device raises it with the upper frame member.

The cross head 30 is provided with two endwise extensible guides 75 and 75', which are correspondingly grooved, as may be observed in Figure 5, and which are retained against the rear surface of the cross head 30 by a holding clip 76 extending substantially lengthwise of the cross head. The outer ends of the members 75 and 75' are provided with knobs 11 whereby movement of these members may be easily accomplished.

For supporting copy moved upwardly by the platen, a skeleton structure is provided, which is adjustable forwardly and backwardly, as the character of the copy might require.

Referring to Figures 1 and 6, a hollow bar 18 having a polygonal interior is oscillatably mounted in the upper ends of the members 7 and 8. Endwise movable in the ends of the bar 18, are polygonally shaped bars 79 having their outer ends extending outwardly of the members 7 and 8. The inner ends of the bars 79 are provided with suitable stops, such as pins, to limit outward movement within the bar 18.

The outer ends of the polygonally shaped bars 79 carry angularly shaped end pieces 80, which end pieces are provided with telescoping bars 81 and 82 so arranged that the polygonal bars 79 may be moved outwardly to their limit of travel with the bars 81 and 82 still in telescoping engagement, to provide an elongated copy guide greater in extent than the length of the cross head 30 of the line guide device C. The cross head 30 is provided with a handle 83 whereby the cross head and the roller 63 may be pulled away from the platen for insertion of copy between the roller and the platen, be the copy a stenographer's notebook or a single sheet of paper.

Copy inserted between the roller and the platen will, on actuation of the platen, be advanced in step by step manner in accordance with the adjustment of the amount of feed of the platen.

Copy may be suspended in front of the typist, without engaging it between the roller 63 and the platen, by means of a hinged member 84 which is secured to the front face of the cross bar by suitable hinges and tensioned by springs 85.

The means for imparting step by step movement to the platen 9 are the means illustrated in applicant's Patent No. 1,715,472, and herein illustrated for convenience, as follows:

At one end of the shaft 10 of the platen, herein illustrated as the right hand end looking at the machine as illustrated in Figure 4, is a ratchet wheel 86 secured by means of set screws 86' to the shaft 10.

Between the end member 8 and the ratchet wheel 86, a plate 87 is oscillatable on the shaft. This plate is provided with a plurality of depressions or holes 88, arranged on a radius, with which cooperates a depression 89 formed in one end of a spring 90 secured by bolts 91 to the end member 8. The plate 87 is oscillatable about its shaft by means of a lever 92 so that any one of

the apertures 88 may be brought into register with the depression 89 in the spring. The lever 92 is formed with an offset 93, behind which moves a pawl 94 pivoted at 95 to the upper end 5 of the reciprocating flat bar 58. A spring 96 is connected between the pawl and the bar 58 to normally maintain the point of the pawl to the left, as viewed in Figure 5, that is in position to engage a tooth of the ratchet 86.

10 The offset 93 of the lever 92 is so fashioned that the point of the pawl 94 normally bears against this offset behind the lever 92, as shown in Figure 5. The angular position of the lever 92, from that shown in Figure 5, to a position 15 in which the detent 89 engages the right-hand depression 88 in the plate 87, controls the number of teeth of the ratchet disposed to action by the pawl point. As the parts are arranged in Figure 5, downward movement of the plate 58 20 will move the pawl downwardly, with its point engaging the tooth immediately beneath the offset portion 93 of the lever. The plate 58 is moved the same distance, every time, by actuation of the key 55.

25 To adjust the platen for two-stage movement, the lever 92 would be swung clockwise, so that the detent 89 would engage the middle depression 88 which would then shift the offset portion 93 of the lever downwardly one space covering 30 the tooth which otherwise would be engaged by the pawl with the lever in the position shown in Figure 5, limiting the advancement of the pawl to a two-stage movement.

35 A clicking pawl 97 is pivoted at 98 and has an outstanding latch 99 adapted to rest against the teeth of the ratchet when the pawl is lowered. In order to maintain the pawl out of clicking engagement, a lever 100 having an end 101 40 adapted to engage with the pawl is suitably pivoted behind the ratchet and has an extremity available for manipulation by the operator. With the clicking pawl in the position shown in Figure 5, there would be no click apparent as the platen is rotated. With the lever 100 swung in 45 counter clockwise direction, to bring the latch 99 against the ratchet teeth, then clicking would occur when the platen is rotated as the spring 115 tends to urge the latch 99 against the ratchet teeth when the lever 100 is swung in counter-clockwise direction moving its projection 101 out 50 of the way of the lower end of the pawl 97.

Figure 5 illustrates the arrangement of parts with the platen set to advance the distance of three ratchet teeth per movement, and without 55 any copy between the roller 63 and the platen.

The device, when extended for use, has the appearance shown in Figure 4. The bars 81 and 60 82 may be endwise adjustable to accommodate the width of the copy used. If this is copy to be advanced in step with the platen, then it is inserted between the platen and the roller 63 65 and aligned with the upper margin of the cross head 30, which margin serves as a line guide. If the copy is not to be moved, then it may be supported between the cross head 30 and the member 84 and suspended in vertical position in front of the typist.

In order to extend the line guide beyond the 70 length of the cross head 30, the members 74 and 75 may be pulled out, as indicated by dotted lines in Figure 4, to afford a line guide comparable with the width of the copy utilized.

The copy holder may be collapsed as follows:

With the copy holder extended, as illustrated 75 in Figure 4, and with the telescoping rods 81 and

82 in full line position and the extensible guides 74 and 75 housed behind the cross head 30, the operator moves the thumb latch 24 backwardly, as viewed in Figure 4, and to the left, as viewed in Figure 2. Such movement, first of all, raises the slotted bar 28 thus rocking the shaft 41 and through it raising the overlying ends of the flattened end portions of the extensions 37 and 39 of the rods E and F, to move them a short distance away from the platen, such for example as 10 to the dotted line position of Figure 2. Such movement relieves whatever binding engagement there may be between the cylindrical portions 59 and 60 of the legs 31 and 32 and the rods E and F. When the bell crank C has been moved to 15 bring the end of the pin 26 against the crank 22 as viewed in Figure 2, pressure of the roller 63 against the platen has been relieved. Continued movement then rocks the rod 21 to swing the crank 29 against the lower ends of the levers 14 20 and 15, which moves the lower ends and the connected bar 18 away from the bar 4 and at the same time projects the plungers 70 to unlatch the bars 62 of the line guide device from contact with the upper ends of the upright portions 34 25 and 36 of the rods E and F. As soon as the lower ends of the levers 14 and 15 are moved away from the bar 4, the upper frame member B drops slightly thus bringing the lower ends of the levers 14 and 15 behind the bar for maintaining the 30 plungers 70 projected and connecting the line guide device with the upper frame member B. The operator then pushes the upper frame member down to the dotted line position of Figure 2, collapsing it together with the line guide device. 35 As the upper frame member B is collapsed, that is, moved downwardly to inoperative position, the bar 58 slides downwardly with it, which it may do, as the pin 56 carried by the link 56 rides in the slot 57 of the bar 58.

40 As the shaft 41 is oscillated, in the manner just described, the mutilated gear 49 rocks the arm 50 to depress the lower end of the bar 56, thus imparting slight rotative movement to the platen, which movement may have some effect in moving the roller 63 away from the platen the instant the plungers 70 are projected.

To extend the holder, all that is necessary to be done is to grasp the knobs 11 and 12 and raise the upper frame member until upward movement 50 is stopped by engagement of the bar 13 of the upper frame member against the bar 4 of the lower frame member. When this contact is established, the lower ends of the levers 14 and 15 swing inwardly over the bar 4, by action of the 55 springs 20, thus latching the upper frame member in extended position, and such lever movement retracts the plungers 70, whereupon the springs 67 urge the roller 63 against the platen 9 with sufficient frictional engagement to hold 60 copy between the roller and the platen.

If desired, a hood may be applied over the platen and the rear side of the upper frame member. Such a hood is herein illustrated at 102. It may be secured in position by screws or any 65 other manner, and may be finished as desired.

70 It will be observed that the copy holder of the present invention is one which may be readily extended or housed by simple movement, and one in which is provided a line guide device for serving the double purpose of a line guide and holding copy against the platen so that step by step movement of the platen will advance the copy a given amount.

75 The resistance offered by the springs 67 is such

that a stenographer's book may be readily inserted between the roller 63 and the platen without straining any of the parts and at the same time enable it to be held with sufficient frictional engagement to be bodily moved by the platen whenever the lever 53 is actuated.

The structure of the present invention is one which may be manufactured largely with stamped parts, thereby providing an article which may be manufactured economically, on a production basis.

The upper frame member latches automatically when it is moved to fully extended position, and may be lowered or housed by manipulation of a single member, to wit, the thumb latch 24.

The bar 58 is normally maintained in upward position by means of a spring 103 connected at one end to the bar and at the other end to a pin 104 on the end member 8 of the upper frame member.

Figure 8 shows the manner of movement of the extensions 37 and 39 of the rods E and F in accordance with oscillatory movement of the shaft 41, as heretofore described.

25 Springs 125 may be applied to the locking bars 62 to normally urge them into locking relation with the bars E and F, when the line guide structure D is in raised position.

In order to secure the skeleton structure in 30 angularly adjusted position with reference to the center of the bar 78, as an axis, a lever 105 is pivoted at 106 to the outer surface of the side member 7, and is provided with a curved end 107 shaped to conform to the projecting end of bar 35 78. A trigger 108 is pivoted at 109 to the member 7 and is arranged with a cam shaped end 110 against the lever 105 in position to move its curved end 107 into tight frictional contact with the bar 78.

40 The hinged member 84 is provided to hold a stenographer's note book in place. When a book is inserted to be read without spacing the book as the shorthand notations are typed, the book is held between the two rollers and the pages 45 to be typed hang outside of the member 84. When the book is to be spaced, line for line, it is held between the rollers, with the pages to be copied behind the member 84, the latter serving as a line guide. When the book is not to be spaced, the roller 9 remains inactive. When the book is to be spaced, the roller 9 is spaced by actuation of the levers 53, 56, and 58.

The invention has been described herein more or less precisely as to details, yet it is to be understood that the invention is not to be limited thereby, as changes may be made in the arrangement and proportion of parts, and equivalents may be substituted, without departing from the spirit and scope of the invention.

60 The invention is claimed as follows:

1. A copy holder for typewriters including a lower frame member and an upper frame member arranged for relative vertical movement, said upper frame member carrying a platen, a line 65 guide device supported adjacent said platen and carrying a roller in contact with said platen, means for supporting said line guide device, said line guide device and said supporting means being relatively vertically movable, means for latching the upper frame member in extended position, means for latching the line guide device in extended position, and a single member for unlatching both of said latching means.

70 2. A copy holder for use with typewriters including a lower frame member and an upper

frame member, said frame members being arranged for relative vertical movement, a platen carried by said upper frame member, means carried by said upper frame member for imparting step by step movement to said platen, a line 5 guide device supported adjacent said platen, said device carrying a roller in contact with said platen, vertically extending legs depending from said line guide device, rods slidably engaged by said legs, means including oscillatable locking 10 bars carried by said legs for latching engagement with the ends of said rods, means for latching said upper frame member in extended position with respect to said lower frame member, and a single instrumentality operable to unlatch both 15 of said latching means.

3. A copy holder, in combination, a base adapted to be removably attached to a typewriter desk, a two part frame on said base comprising a lower member and an upper member 20 arranged for vertical sliding movement of the upper member on the lower member, latching members carried by said upper frame member for engaging with the lower frame member to hold said upper frame member in raised or operative 25 position, a feed platen mounted in said upper frame member, means for holding copy against said platen including a cross head member and a roller mounted in said cross head for engagement with said platen, legs depending from said 30 cross head, upright rods on said base in telescopic engagement with said legs, latching members carried by said legs, spring means for normally urging said members into latching engagement with said rods when said cross head 35 is in extended position with said upper frame member, spring means acting against said rods to exert pressure between the roller and platen to feed copy by rotation of the platen, means for actuating said first latching members to unlatch 40 said upper frame member, and means operable by actuation of said first latching members to unlatch the latching members carried by said cross head legs, said last means engaging said cross head to connect it to the upper frame 45 member for simultaneous vertical movement with it.

4. A copy holder, in combination, a base adapted to be removably attached to a typewriter desk, a two part frame on said base comprising a lower member and an upper member arranged for vertical sliding movement of the upper member on the lower member, latching members carried by said upper frame member for engaging with the lower frame member to hold said upper frame member in raised or operative 50 position, a feed platen mounted in said upper frame member, means for holding copy against said platen including a cross head member and a roller mounted in said cross head for 55 engagement with said platen, legs depending from said cross head, upright rods on said base in telescopic engagement with said legs, latching members carried by said legs, spring means for normally urging said members into latching engagement with said rods when said cross head 60 is in extended position with said upper frame member, spring means acting against said rods to exert pressure between the roller and platen to feed copy by rotation of the platen, means for 65 actuating said first latching members to unlatch said upper frame member, means operable by actuation of said first latching members to unlatch the latching members carried by said cross 70 head legs, said last means engaging said cross 75 head.

head to connect it to the upper frame member for simultaneous vertical movement with it, spring means for resetting said first mentioned latching members, and said first mentioned 5 spring means being effective for resetting said second mentioned latching members when the upper frame member has been raised to operative position.

5. In a device of the class described, in combination, a frame including telescoping members arranged for relative vertical movement, means on the upper of said members for latching engagement with the lower of said members to latch said members in extended position, a line 10 guide member including telescoping members arranged for relative vertical movement, means on one of said latter telescoping members for latching engagement with the others of said latter telescoping members to latch said line guide 15 member in extended position, means for unlatching said frame members, means operable by said last mentioned means for unlatching said line guide members, and means effective when the line guide members are unlatched for connecting 20 the upper of said line guide members with the upper of said frame members to cause simultaneous movement to collapsed position.

6. In a copy holder in combination with a base supporting a pair of upright rods, a copy support 25 vertically movable on said rods from extended operative position to collapsed inoperative position, a platen carried by said copy support, other upright rods supported on said base and carrying

a line guide structure, said line guide structure being vertically movable on said other rods to extended operative position and collapsed inoperative position, said line guide structure carrying a roller bearing against said platen when said parts are in extended operative position, adjustable spring means acting against said other rods for varying the pressure of said roller against said platen, means for latching said support in extended position, other means for latching said line guide structure in extended position, and a single instrumentality for unlatching both of said latching means. 10

7. In a copy holder including a base, a pair of upright rods thereon, a platen carrying part vertically movable on the rods between a raised operative position and a collapsed inoperative position, a platen supported by said part, other vertical rods on said base carrying a line guide structure movable on said other rods between a 15 raised operative position and a collapsed inoperative position, said line guide structure carrying a roller normally engageable with said platen when said parts are in operative position, means latching said platen in operative position, other 20 means latching said line guide structure in operative position, a single instrumentality for unlatching both of said latching means, and means for connecting said platen carrying part and said line guide structure together when said latching 25 means are unlatched to cause simultaneous collapse of said line guide structure and parts. 30

STEPHEN SATTLER.
